SLEEPING BAG

Cornell M. Miller, Philadelphia, Pa.

Application January 8, 1947, Serial No. 720,891

6 Claims. (Cl. 2—69.5)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates primarily to sleeping bags and the like and to a method of manufacturing the same, but obviously the method could, with minor variations, be advantageously employed in the manufacture of various articles of wearing apparel.

One object of the invention resides in the provision of a sleeping bag having maximum internal length for the length of material employed in its construction.

Another object of the invention consists in so constructing a sleeping bag that wastage of material is reduced to a minimum.

A still further object of the invention resides in a form of sleeping bag wherein the full width of the material may be used for the back panel of the bag and the width of the front panels will be increased or decreased, as may be necessary to produce a bag or other garment in an extremely simple and economical manner.

A further object of the invention consists in the provision of a sleeping bag which is so designed as to give the desired fit to the contour of the head.

Another object of the invention resides in the construction of a sleeping bag in which the sewing operation in the head and shoulder portions of the bag is facilitated by materially reducing the aggregate length of seams.

Still another object of the invention consists in the provision of a sleeping bag or the like in which the shoulder portion is of draped design so as to give the desired flexibility and softness in that portion of the bag.

Other objects and advantages of the invention will be apparent from the following description when taken in connection with the accompanying drawings, in which:

Figure 1 is a perspective view of a sleeping bag embodying the present invention;

Figure 2 is a plan view of the back and front panels of a bag and showing the relative positions of the panels; and

Figures 3 and 4 are plan views, on a reduced scale, showing two methods of cutting two bag sections from a minimum amount of material.

Referring to the drawings in greater detail the numeral 1 designates the back section or panel of the novel sleeping bag, and the numeral 2 designates two identical front panels.

In the method of cutting the panels, as shown in the lay of Fig. 3 shows two back portions formed by

2

in Figure 3, the material employed is a fabric of 36" width and two back panels and four front panels are indicated as cut from a particular length of cloth. The back panels 1 are therefore 36" wide and the front panels, which are formed of half-widths, are 18" wide.

In the pattern lay of Figure 4, a fabric of 61" width is employed and the back panels are indicated as formed of half-widths (30½ inches) and the front panels are of quarter-widths (15¼ inches). These dimensions, of course, as well as those set forth in the preceding paragraph are intended to be merely illustrative of the invention rather than limiting.

15 The head end of each back panel 1 is provided with substantially semi-circular cutouts 3 disposed symmetrically on opposite sides of the center line of the panel and adapted to conjointly form a face opening when the bag is completed. The head end of the back panel is also preferably formed with a rounded V-notch 4 at the center line for a purpose to be described hereinafter.

As clearly indicated in Figs. 2 to 4, inclusive, 25 the front panels 2 are of rectangular formation at the head end and are beveled or tapered at the foot end as indicated by numeral 2'. This shaping of the front panels provides a sleeping bag of the mummy type, as indicated in Fig. 1, but it will be obvious that the present invention may be embodied in sleeping bags of generally rectangular formation throughout by eliminating the tapered ends of the front panels and making them of uniform width throughout.

30 Before proceeding further with the description of the formation of the bag, the manner of cutting the several sections so as to avoid wastage of material will be elaborated upon. The piece of cloth from which the bag is manufactured (Figure 3) is assumed to have a width of 36", and the back panels 1 are cut from the full width of the material as shown, thereby providing back panels of 36" width. The front panels, as hereinbefore mentioned, are 18" wide and four of them may therefore be cut from a single width of the cloth of a length somewhat greater than the length of a single front panel and dividing the same longitudinally as indicated by the line 5 in Fig. 3 and dividing the sub-sections diagonally as indicated by the lines 6. By thus marking and cutting the cloth, two pairs of front panels are provided with the inclined ends of one pair being contiguous and disposed within the inclined ends of the other pair. The pattern 35 lay of Fig. 3 shows two back portions formed by

the transverse cut 7; this being done merely for the purpose of showing two back panels necessary for use with the four front panels 2, also cut from a single width of the cloth. In forming the back panels 1, one narrow edge of each of them is formed with the substantially semi-circular cutouts heretofore referred to and the rounded V-notches 4 also previously mentioned. It will thus be seen that by following the pattern as indicated in Fig. 3, practically no wastage of material is involved in the cutting of the several sections of the present sleeping bag.

The manner of cutting the panels as illustrated in Figure 4 is substantially the same as that heretofore described except that advantage is taken of the greater width of material (61 inches) by making four back panels of 30½" width and four pairs of front panels of 15¼" width from a particular length of material and reversing the positions of the panels on the next length of material so as to take care of the extra length of the four front panels as compared to the back panel. It will be understood, of course, that in the cutting operations as indicated in Figures 3 and 4 the material is first marked off and the desired number of superposed layers of cloth are cut in accordance with the markings.

In order to attain several of the advantages set forth herein, the front panels may be considered as being positioned with respect to the back panel 1 in the manner shown in Figure 2. In this relationship, the panels 2 are spaced from the head end of panel 1 a distance corresponding to the width of the end 9 of the panels, and in stitching the bag the edge 9 may be first stitched to the adjacent edge of panel 1, as indicated at 11 in Figure 1, and the line of stitching then continued to join the straight edge of the front panel and its tapered edge 2' to the back panel as indicated by numeral 12 in Figure 1 and the arrows of Figure 2.

In stitching the bag as just described, the corners of the head end of the back panel 1 must necessarily be folded along the lines 10, thus bringing the edges containing the cutouts 3 closely adjacent each other. These edges may then be stitched together along the line 13 to provide the face opening 14. This line of stitching also includes the sides of the rounded V-notch 4 which serves to provide a fullness in the head end of the bag so as to permit the head of the occupant to be positioned more closely adjacent the end wall of the sleeping bag, thereby permitting the use of bags of slightly less overall length than would otherwise be possible.

The opposite end of the panel 1 is folded upon itself and the edges secured together by a line of stitching 15, and the bag may be completed by the addition of a separable fastener 16, such as a zipper, to the free edges of the front panels and the folded edges 17 of the back panel which are disposed below the face opening 14.

From the foregoing description taken in connection with the accompanying drawings, it will be apparent to those skilled in the art that I have devised a sleeping bag and process of manufacturing the same which reduce wastage of material to a minimum; that maximum internal length commensurate with the amount of material used and shaping of the head portion are provided; that the various panels are of such design and dimensions as to permit of the minimum use of material; and that the elimination of seams in the shoulders of the bag will provide

a better draping of the material of the head end of the bag.

In accordance with the patent statutes, I have described what I now consider to be the preferred form of the sleeping bag and the process of manufacture, but inasmuch as various minor changes may be made in the details of construction without departing from the spirit of the invention, it is intended that all such details be included within the scope of the appended claims.

I claim:

1. A sleeping bag blank formed from a back panel of substantially rectangular outline provided with complementary cutouts in the head end to form a face opening, front panels of substantially rectangular formation at the head end, the front panels being stitched to the side edges of the back panel and each spaced from the head end of the latter a distance equal to the width of each front panel.

2. A sleeping bag blank formed from a back panel of substantially rectangular outline, front panels of substantially rectangular formation at the head end and tapered away from the back panel at the foot end, the front panels being stitched to the side edges of the back panel and each spaced from the head end of the latter a distance equal to substantially the width of each front panel.

3. A sleeping bag comprising a back panel of substantially rectangular outline, front panels of substantially rectangular formation at the head end, said front panels being stitched to the side edges of the back panel but each spaced from the head end of the back panel a distance equal to the width of each of the front panels, lines of stitching joining the adjacent edges of the back and front panels at the head end thereof, means for closing the foot end of the bag, and releasable fastening means for joining the free edges of the front panels.

4. A sleeping bag comprising a back panel of rectangular outline provided with complementary cutouts in the edge at its head end, front panels of substantially rectangular formation at the head end, said front panels being stitched to the side edges of the back panel but each spaced from the head end thereof a distance corresponding to the width of each of the front panels, lines of stitching joining the adjacent edges of the back and front panels at the head end and adjoining portions of the edge of the head end of the back panel, means for closing the foot end of the bag, and releasable fastening means for joining the free edges of the front panels.

5. A sleeping bag comprising a back panel of rectangular outline provided with complementary cutouts in the edge at the head end on opposite sides of its mid-portion and a V-notch at the mid-portion, front panels stitched to the side edges of the back panel but each spaced from the head end thereof a distance corresponding to the width of each of the front panels, lines of stitching joining the adjacent edges of the back and front panels at the head end thereof and the edge portions of the head end of the back panel on opposite sides of its mid-portion, and means for closing the foot end of the bag.

6. A sleeping bag comprising a back panel of substantially rectangular outline, front panels of substantially rectangular formation at the head end and tapered away from the back panel at the foot end, said front panels being stitched to the side edges of the back panel but each spaced

from the head end of the back panel a distance corresponding to the width of the rectangular portions of each of the front panels, lines of stitching joining the adjacent edges of the back and front panels at the head end of the bag, means for closing the foot end of the bag, and releasable fastening means for joining the free edges of the front panels.

CORNELL M. MILLER.
